(57) **CLAIM**

The ornamental design for a U-shaped exercise weight bar, as shown and described.

DESCRIPTION

FIG. 1 is a perspective view of a mounted U-shaped exercise weight bar showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right-side elevation view thereof;

FIG. 7 is a left-side elevation view thereof;

FIG. 8 is a perspective view of the U-shaped exercise weight bar of FIG. 1 shown unmounted;

FIG. 9 is a top plan view thereof;

FIG. 10 is front elevation view thereof;

FIG. 11 is a bottom plan view thereof;

FIG. 12 is a right-side elevation view thereof;

FIG. 13 is a rear elevation view thereof; and,

FIG. 14 is a left-side elevation view thereof.

In FIGS. 9-14, the U-shaped weight bar is shown removed from the mount for clarity of disclosure.

1 Claim, 6 Drawing Sheets
